UNITED STATES PATENT OFFICE.

JAMES M. ROBERTS, OF ST. JOSEPH, MISSOURI.

WIRE-STRETCHER.

1,252,953.

Specification of Letters Patent.

Patented Jan. 8, 1918.

Application filed September 15, 1917. Serial No. 191,637.

To all whom it may concern:

Be it known that I, JAMES M. ROBERTS, a citizen of the United States, residing near St. Joseph, in the county of Andrew and 5 State of Missouri, have invented certain new and useful Improvements in Wire-Stretchers, of which the following is a specification, reference being had therein to the accompanying drawing.

10 My invention relates to improvements in wire stretchers and staple pullers, combined; and the objects of my improvements are, first; to provide a simple, substantial and durable wire stretcher, which shall be held in position, against a fence post or 15 similar object by the tension of the stretched wire, thereby leaving both hands of the operator of the stretcher free, while driving a staple in said post, for holding the stretched 20 wire in place, second; to so construct the stretcher, that it shall be adapted for use in stretching both fence and telephone wires, third; to so form the gripping members that the thereby gripped wire can not escape 25 from between said members while it is being gripped, fourth; to provide a staple puller, formed with the body of the wire stretcher, for pulling staples from posts and the like, fifth; to so form an implement of this class, 30 that it shall be compact and cheap in cost of manufacture.

I attain these objects by the mechanism illustrated in the accompanying drawing, in which:—

35 Figure 1 is plan view of the stretcher and a transverse section of a fence post, with a fence wire stretched thereagainst. Fig. 2 is rear view of the stretcher, seen in Fig. 1. Fig. 3 is an end view of the stretcher seen in Fig. 1, looking toward the right. Fig. 4 is a side view of the stretcher with the parts in position stretching a telephone wire.

40 Referring to Figs. 1 and 3, the body 1, of the stretcher, has handle 2, fulcrum points 3 and grip members 4 and 4', formed therewith. Said members have the projected edges 4'' and 4'a formed therewith, which overlap the adjacent edges of the oscillatable 45 grip members 5 and 5' respectively. Said oscillatable members have wire guides 6 and 6', respectively formed therewith.

50 Body 1 has the two mortises 1', formed therein, in which grip members 5 are oscillatably mounted. One end of each of said

members is pivoted on bolt 7, which is passed through said mortised portion of said body.

Grip members 4 and 5 grip the fence wire 8, for stretching the same across the face 60 side of post 9.

Cant hook 10 has ratchet teeth 10' formed on one edge thereof, which engage lug 10''. Said lug is formed in the mortise 10'a, which is formed through body 1. This provides 65 hook adjusting means, whereby the reach of said hook is adjusted.

The bifurcated brace 11 has the upper ends of its upper bifurcations pointed for adapting the same to be engaged with the 70 face side of post 9. The lower bifurcations of said brace each have a slot 11' formed therethrough, along one edge of which the ratchet teeth 11'' are formed. Said teeth engage bolt 7, which forms brace adjusting 75 means, whereby the reach of said brace is adjusted.

Bolt 7 is secured in place by the two collars 7' which are secured on the ends of 80 said bolt by pins 7''.

Claws 12 are secured on one end of body 1, and are adapted to be forced between wire 8 and post 9 while astride staple 13, for drawing said staple from said post.

Body 1 has bolt 14 formed therewith and 85 extending through mortises 1', which bolt is engaged by the ratchet teeth 10', of cant hook 10, as seen in Fig. 4; for use in stretching a telephone wire 15, as hereinafter described.

90 In operation, the operator places fulcrum points 3 against post 9, and passes the free end portion of wire 8, between grip members 4 and 5. He then presses the wire guide 6 toward said wire, thereby pressing 95 the toothed edge of member 5 in close contact with said wire. Thereafter, by handle 2, with one hand, he swings body 1, fulcrumed on fulcrum points 3, until said wire is tightly stretched. He then, with the 100 other hand adjusts the reach of cant hook 10, as required, and thereafter drives the point of said hook into post 9, after which the tension of wire 8 holds the wire stretcher in place. Said operator, then, with 105 the usual tools and the use of both hands, drives staple 13 into post 9, for holding said wire in place.

He then releases cant hook 10 from said post and by wire guide 6, moves member 5 110

from contact with wire 8, after which the operator repeats the described operations, for securing said wire to another post.

Where the shape of the post is such as to render cant hook 10 inadequate to hold the parts in the position shown in Fig. 1, the pointed ends of brace 11 are swung into engagement with the face of the post, for additionally bracing the wire stretcher 10 against the strain of wire 8.

When used as a telephone wire stretcher, the parts are placed in the position seen in Fig. 4, with fulcrum points 3 and hook 10 engaging the surfaces of cross arm 16.

Similar operations are performed with grip members 4' and 5' and the wire guide 6', for engaging wire 15 between said members, after which said wire is stretched adjacent to insulator 17, as previously described. Said wire is then secured in the usual manner, by a tire wire, (not shown,) to insulator 17. The wire stretcher is removed from the position shown in Fig. 4, by performing releasing operations, similar to the ones already described.

Having fully described my invention, what I claim as new, and desire to secure by Letters Patent is:—

1. In a wire stretcher, a body adapted to be used as a lever; a pair of fulcrum points formed with said body, said points being adapted to act against a post as a fulcrum for said body; grip members carried on said body for gripping a wire; a handle on one end of said body whereby the latter is swung on said fulcrum points for stretching said wire; holding means connected with said body, the free end of said holding means

being adapted to engage the side of said post for holding said body against the strain of said stretched wire; and auxiliary holding means comprising a bifurcated brace adjustably pivoted on said body, the ends of the bifurcations of said brace being adapted to be driven into said post for assisting in holding said body against the strain of said stretched wire.

2. In a wire stretcher, a body adapted to be used as a lever, a pair of fulcrum points formed with said body, said points being adapted to act against a fixed object as a fulcrum for said body; a handle formed on one end of said body; wire gripping members connected with the opposite end of said body for gripping a wire, said body being adapted to be swung by said handle and thereby move said grip members for stretching said wire; a mortise formed in said body; a cant hook detachably held in said mortise; a pair of other mortises formed in the intermediate portion of said body; a grip member oscillatably mounted in each one of said mortises; a bolt formed with said body extending through the last mentioned mortises, said cant hook being adapted to be removed from the first mentioned mortise and to be passed through one of the last mentioned two mortises and to have its hooked end engaged with said fixed object for holding said body against the strain of said stretched wire; and ratchet teeth formed on one edge of said cant hook said teeth being adapted to engage said bolt for adjusting the reach of said hook.

In testimony whereof I affix my signature. 75
JAMES M. ROBERTS.
